[57] CLAIM

The ornamental design for the storm window molding,
or similar article, substantially as shown and described.

DESCRIPTION

FIG. 1 is a perspective view of the storm window molding
or similar article of this invention assembled to
maintain a window of glass, plastic, etc. in proper position;

FIG. 2 is a perspective view of the glazing frame which
mates with a tape frame to form the assembled molding;
and

FIG. 3 is the tape frame, showing an adhesive strip tape
on the bottom thereof, which mates with the glazing
frame of FIG. 2.

The window and strip shown in broken lines in the
drawing are disclosed for illustrative purposes only and
form no part of the claimed design.
